Lansing Lee Porter INVENTOR.

UNITED STATES PATENT OFFICE.

LANSING LEE PORTER, OF EVANSTON, ILLINOIS.

DESIGN FOR A GEOMETRICAL BLOCK.

SPECIFICATION forming part of Design No. 23,086, dated February 27, 1894.

Application filed November 21, 1892. Serial No. 452,730. Term of patent 7 years.

To all whom it may concern:

Be it known that I, LANSING LEE PORTER, a citizen of the United States, residing in the city of Evanston, in the county of Cook and State of Illinois, have invented and produced 5 a new and original Design for a Geometrical Block, of which the following is a specification, reference being had to the accompanying drawings, forming a part thereof.

- Figure I. shows the design from one point of view, and Figs. II. and III. show the same as viewed from different points.

The design, described in geometrical terms, is a regular dodecahedron having a five-faced

pyramid erected on each of its twelve pentagonal faces as a base. That is, it is a twelve-pointed star, symmetrical on all sides, showing twelve five-pointed stars when viewed from all sides. The feature of the design is the outline of these twelve pyramids or points. 15 20

What I claim is—

The design for a geometrical block herein shown and described.

LANSING LEE PORTER.
